PRE-ASSEMBLED RESIDENCE

Kenneth W. Goodrich, 1255 W. Grand River,
East Lansing, Mich. 48223

Filed Oct. 10, 1968, Ser. No. 13,930

Term of patent 14 years

Int. Cl. D25—04

U.S. Cl. D13—1

FIG. 3

FIG. 4

FIG. 5

I claim:

The ornamental design for a pre-assembled residence, as shown and described.
